UNITED STATES PATENT OFFICE.

DAVID P. PERRY, OF CHICAGO, ILLINOIS.

ELECTRIC HORN.

1,130,676.

Specification of Letters Patent.

Patented Mar. 2, 1915.

Application filed November 3, 1905. Serial No. 285,766.

To all whom it may concern:

Be it known that I, DAVID P. PERRY, a citizen of the United States of America, and resident of Chicago, Illinois, have invented a certain new and useful Improvement in Electric Horns, of which the following is a specification.

My invention contemplates an improved horn, or other similar sound-producing device, operated by electricity. It also contemplates an improved horn or similar device provided with a diaphragm and means for vibrating said diaphragm.

In the hereinafter described particular embodiment of my invention, a horn or resonator is provided, and across the rear end of the same I provide a diaphragm. Associated with said diaphragm is an electric buzzer or circuit-breaker having its armature connected by a spring with the center of the diaphragm. With this arrangement, the energizing of the electric buzzer, and the consequent vibration of its armature, will cause such vibration to be communicated to the diaphragm, with the result that the horn will give out a musical tone.

The nature and advantages of my invention will, however, hereinafter more fully appear.

In the accompanying drawings, Figure 1 is a perspective of a horn embodying the principles of my invention. Fig. 2 is an enlarged section of the same. Fig. 3 is a view of the rear end of the horn.

As thus illustrated, the horn or resonator A is provided at its rear end with a thin and preferably springy or resilient diaphragm B. In order that the vibrations of said diaphragm may not be mechanically or metallically communicated to said horn, it is preferably clamped to the horn between the ring C and the inner edge of the clamping ring D. These two rings can be made of rubber, fiber or other materials which will insulate the diaphragm from the horn, and which will cause the vibrations of the diaphragm to only be communicated through the air to the metal sides of the horn. The electric buzzer or circuit breaking device E may be of any suitable known or approved character. As shown, it has an armature e and the usual circuit-breaking contacts e' and e". When the armature is attracted, the circuit is broken, and the spring e³ upon which the armature is carried immediately restores

the latter to its normal position, and thus recloses the circuit. This rapid make-and-break action in the circuit of the electro-magnets of the buzzer or circuit-breaker produces a very rapid vibration of the armature e in the usual or well-known manner. This armature is connected by a spring F with the center of the diaphragm B. It is also preferable to provide the said spring with a weight f. With this arrangement, the vibrations of the armature e are communicated to the diaphragm B, with the result that the horn gives forth a musical tone. It will be understood, of course, that the period of vibration of the buzzer or circuit-breaker can, if desired, be nicely adjusted to the pitch of the horn,—that is to say, adjusted so as to correspond with the natural period of vibration of the horn or the column of air within the same. This can be done, it will be seen, by varying the tension of the spring F, or perhaps by varying the weight of the ball f. The tension of the spring e³ may be changed or varied in order to obtain the best results. I have obtained good results with the parts proportioned and constructed substantially as shown in the drawings.

The diaphragm closes the mouth or end of the horn, but its vibration, when properly adjusted, will cause the horn to give forth a musical tone of a certain pitch, the loudness of which will depend upon the amplitude of the vibrations of the diaphragm. With the construction and arrangement shown, I find that the tone can be increased in loudness by increasing the strength of the current for the buzzer or circuit-breaker, and that the tone can be modified by simply using a weaker electric current.

It will be understood, of course, that the mouth of the horn and the mechanism for operating the diaphragm can all be suitably inclosed in a casing G. The wires or conductors H for supplying the buzzer or circuit-breaker with suitable current can be passed through the side of said casing.

While I have illustrated and described one particular embodiment of my invention, it is to be understood that I do not wish to limit myself to such exact construction.

What I claim as my invention is:

1. In a horn; the combination of a resonator, a thin and springy or resilient diaphragm closing the mouth of said resonator,

and an electric buzzer or circuit-breaking device, spring means for connecting said circuit breaking device with said diaphragm for communicating vibration thereto for the purpose of vibrating the column of air within the horn.

2. In a horn, the combination of a thin sheet-metal member made hollow with a flaring forward end and a slightly enlarged mouth or rear end, a flexible metal diaphragm closing the mouth of said member, means for preventing the vibrations of the diaphragm from being mechanically communicated to said sheet-metal member, and means back of the diaphragm for mechanically vibrating the same.

3. In a horn, the combination of a diaphragm, an electric buzzer or circuit-breaking device, and a spring connection between said diaphragm and the armature of said electric buzzer or circuit-breaking device.

4. In a horn, the combination of a diaphragm, an electro-magnet, a spring-mounted armature for said electro-magnet, circuit-controlling contacts operated by said armature, a spring connecting said armature with said diaphragm, and a weight carried by said spring.

5. In an electric alarm device, a horn, a diaphragm arranged in operative relation thereto, an electromagnet, an armature influenced by said electromagnet and an elastic intermediary part fixed on the one hand to said diaphragm and on the other hand to

said armature, whereby the vibrations of the armature are mechanically transmitted to the diaphragm in such a manner that the vibrations of the diaphragm may differ from those of the armature.

6. In an electric alarm device, a horn, a diaphragm arranged in operative relation thereto, an electormagnet, an armature influenced by said electromagnet and a spring fixed on the one hand to said diaphragm and on the other hand to said armature, whereby vibrations of the armature are mechanically transmitted to the diaphragm in such a manner that the vibrations of the diaphragm may differ from those of the armature.

7. In an electric alarm device, a horn, a diaphragm arranged in operative relation thereto, a lever adapted to swing, an armature attached to said lever and influenced by said electromagnet, and a spring fixed on the one hand to said diaphragm and on the other hand to said lever, whereby vibrations of the armature are mechanically transmitted to the diaphragm in such a manner that the vibrations of the diaphragm may differ from those of the armature.

Signed by me at Chicago, Cook county, Illinois, this 21st day of October 1905.

DAVID P. PERRY.
